VENDING MACHINE

Jack E. Sellinger, Malverne, and Herman H. Richman, Brooklyn, N. Y., assignors to Naps Specialties Corporation, Brooklyn, N. Y., a corporation of New York

Application October 19, 1939, Serial No. 300,114

5 Claims. (Cl. 312—48)

This invention relates to vending machines and more particularly to such machines as vend rolled or similar articles, although it will be obvious that the invention is also applicable to machines for vending various commodities.

One object of the invention is to provide a machine which is simple in construction and operation.

It is a further object of the invention to provide a machine having greater capacity for commodities to be vended than machines of the same type as at present constructed.

A feature of the invention resides in the provision of a new and novel article delivery mechanism together with means for mounting the same within the machine in a manner whereby it may be readily removable and replaced. This feature we consider important since it permits of the replacement of a delivery mechanism when it has become out of repair without rendering the machine inoperative over long periods and without unnecessary delay during the repairing of an inoperative delivery mechanism.

A further feature of the invention resides in the provision of a novel storage arrangement of the articles to be vended and the novel manner in which they are maintained in their respective storage compartments by the delivery mechanism.

Still a further feature of the invention resides in a novel delivery mechanism which acts to completely empty each storage compartment in a successive manner, that is to say, that the compartments are completely emptied of articles to be dispensed in a successive manner as will be hereinafter more specifically explained.

Other features of the invention relate to certain novel and improved constructions, arrangements and combinations of parts hereinafter described and particularly pointed out in the claims, the advantages of which will be readily understood and appreciated by those skilled in the art.

The invention will be clearly understood from the accompanying drawings illustrating the invention in its preferred form and of the following detailed description of the construction therein shown.

In the drawings:

Figure 1 is a perspective view of a vending machine constructed in accordance with the present invention.

Figure 2 is a fragmentary view in rear elevation of a portion of the front wall of the machine,

Figure 3 is a fragmentary view in front elevation on an enlarged scale with a portion of the cover broken away.

Figure 4 is a detail vertical sectional view on an enlarged scale taken substantially on the line 4—4 of Figure 1.

Figure 5 is a horizontal sectional view on an enlarged scale taken substantially on the line 5—5 of Figure 1.

Figure 6 is a detail view in elevation on an enlarged scale illustrating the operation of the delivery mechanism, and;

Figure 7 is a distended perspective view illustrating the means for retaining the delivery mechanism in operative position and the locking means of said delivery mechanism.

Referring more specifically to the drawings, the reference numeral 10 designates a cabinet which is of relatively long and narrow form. The cabinet has a removable front wall 11 which has a downwardly turned flange 12, see Figure 3, which in turn may be received in a slot or opening in the top wall 13 of the cabinet, the slot or opening not being herein illustrated. The removable front wall 11 provides access to the interior of the cabinet for loading the same and for repair or removal of the parts thereof, and this wall is retained in position to close the cabinet 10 by means of a suitable locking mechanism 14.

The interior of the cabinet is provided with a plurality of spaced vertically disposed partitions 15 which divide the upper portion of the cabinet into a plurality of relatively narrow compartments 16 in which the articles to be vended are stored, the articles being designated 17 in the drawings. At each side of the compartment at a point below the lower ends of these partitions there are guides 18 which serve to direct articles from the outer compartments 16 towards the center of the machine and to the delivery mechanism thereof. The lower portion of the cabinet 10 is divided by means of partitions 19 and 20 into a coin receiving compartment 21 and an article delivering compartment 22. The coin receiving compartment 21 is closed by the front wall 11. However, the front wall 11 has an opening 23 which provides access to the article receiving compartment 22 in order that articles delivered thereto by the delivery mechanism may be withdrawn therefrom.

The reference numeral 25 designates a coin controlled mechanism. This coin controlled mechanism may be of any conventional type. 55 This coin controlled mechanism is carried by

the front wall 11 of the cabinet and has a shaft 27 which projects inwardly of the cabinet. This shaft is of the stub shaft type and forms, together with other constructions to be herein-after described, means for steadyng the drum of the article delivery mechanism. This shaft 27 carries an arm 28, the outer free end of which is slightly offset as at 29 for a purpose to be herein-after described. The shaft 27 and its arm 28 may be rotated by the coin controlled mechanism upon the insertion of a proper coin or token therein and a turning of the handle 30 thereof.

The delivery mechanism consists of a drum like member which comprises two end plates 31 and 32 of circular form. These end plates are suitably secured to a hollow spindle 33, the ends of which are reduced as at 34 in Figure 5. The hollow spindle 33 is mounted upon a suitable support 35 which in turn is rigidly secured to the rear wall of the cabinet as at 36 by spot welding or the like. This support is carried by a plate 37 and also carried by said plate 37 there is a bushing 38 having an opening to receive the reduced rear end of the spindle 33. By this construction, the spindle 33 is rigidly secured to the rear wall of the cabinet.

The forward end of the spindle 33 is supported in an opening 40 in a bracket 41. This bracket 41 is removably secured in position upon the partition 20 by means of a suitable bolt 42 and wing nut 43, the bolt 42 sliding in a slot 44 in the partition 20 as best illustrated in Figure 6. By this construction and arrangement of parts, it is obvious that merely by loosening the wing nut 43, the entire delivery mechanism may be readily removed from the cabinet and if necessary, be replaced by another delivery mechanism.

The end plates 31 and 32 of the drum of the delivery mechanism are circular in form and they are connected by a plurality of spaced groups of rollers 45. In the present embodiment of the invention there are three rollers in each group and the groups are so spaced from one another as to provide intervening spaces 46 of a size sufficient to receive a single article only to be vended by the machine. The plates 31 and 32 have centrally disposed openings for the reception of the spindle 33 and when said drum is in position on the spindle, the ends of the spindle will occupy positions in the openings of the drum. By this means, the drum is freely rotatable upon the spindle and the parts are so positioned that the drum is centrally disposed with respect to the several compartments 16.

The plate 31 is provided with a plurality of stops 50. These stops 50 are equi-distantly spaced and are located one at each group of rollers, each stop being in radial line with the central roller of its respective group.

As best illustrated in Figure 4, these stops project forwardly of the end plate 31 by which they are carried and are yieldingly movable in a direction axially of the drum. Each stop comprises a housing 51 in which is mounted a coil spring 52. Each stop has a head member 53 and extending rearwardly from each head 53 there is a stem 54 which extends through an opening in the rear end wall of the housing 51. The stem 54 has a head upon its extended end and interpositioned between the head 54 and the end wall of the housing, there is a coil spring 55. By this construction and arrangement of parts it will be obvious that the stops 50 are free to move in a direction axially of the drum but

in their normal position stand extended from the front end wall of the drum as illustrated in Figures 4 and 5.

The bracket 41 heretofore mentioned is of right angular construction having a base member 56 and a vertical extension 57. The base member 56 carries the bolt 42 heretofore mentioned. The vertical extension 57 of the bracket is cut along the lines designated 58 and 59 to provide a tongue 60 which is bent slightly forwardly as best illustrated in Figure 7. The vertical extension 57 is also provided with an arcuate slot 61, the purpose of which will be herein-after described.

The bracket 41 in addition to supporting the forward end of the drum of the delivery mechanism also carries a locking mechanism and a releasing mechanism for the drum, and this mechanism will now be described.

The locking mechanism consists of a pivoted lever 65 which is pivotally mounted by means of a bolt 66 which passes through an opening 67 in said lever and engages in threaded openings 68 in the vertical extension 57 of the bracket 41. This pivoted lever 65 has a tail extension 70 to which a spring 71 is connected at one end as at 72, the other end of the spring being connected to a pin or the like 73 carried by the vertical extension 57 of the bracket. The pivoted lever 65 has a notch 74 for the reception of the stop 50 heretofore mentioned and beyond the notch there is a nose piece 75 adapted to engage a stop 76 carried by the vertical member 57 to limit the pivotal movement of the pivoted lever 65 about its pivotal point. By this construction the pivoted lever 65 is held normally in a position where its notch 74 will coincide with the arcuate slot 61 in the vertical extension 57 of the bracket 41.

With the parts in their normal position of rest, the stop 50 will be engaged in the notch 74 of the pivoted lever 65 and by reason of such engagement the drum will be locked against rotation.

Means is provided to operate the mechanism to release the drum, thus discharging articles from the machine and this means comprises a vertical lever 80. This lever 80 is pivotally mounted upon the pivoted lever 65 by means of a bolt or the like 81. Projecting from the upper end of the lever 80, there is an arm 82 which is offset as at 83 with respect to the plane of the body portion of the lever while the lower end of the lever 80 is extended to a point below the lower edge of the pivoted lever 65 as at 83'. A spring 84 is connected at one end to the lower end of the vertically disposed lever 80 and at the other end to the spring 71. This lever 80 also has a right angular extension 85' which overlies the top edge of the pivoted lever 65 when the parts are in their assembled position illustrated in Figures 3 and 6 of the drawings.

The operation of the machine will now be described.

Referring to Figure 3 it will be noted that there are two articles in the drum of the delivery mechanism and that these two articles were taken from the left hand compartment 16 in said figure. The drum is locked against rotation by reason of engagement of one of the stops 50 in the notch 74 of the pivoted lever 65 as illustrated in Figure 6. The arm 28, heretofore mentioned, is in its dotted line position in which it is shown in Figure 6, in which position it overlies one of the stops 50 also as illustrated in Figure 6.

With the parts in these positions, the purchaser inserts a coin into the coin controlled mechanism and grasping the handle 30 thereof, turns the handle in a clockwise direction. This action rotates the stub shaft 27 and with it the arm 28 as indicated by the arrow A in Figure 6. As the handle 30 of the coin controlled mechanism is turned, the short end 85 of the arm 28 will engage the arm 82 of the vertically disposed lever 80 to rock said lever to the left in Figure 6 upon continued clockwise movement of the arm 28. This action, through the medium of the right angular extension 85' of the vertically disposed lever 80 rocks the pivoted lever 65 about its pivotal point in a downward direction as indicated by the arrow B in Figure 6 to a point where the stop 50 is free to pass from the notch 74 of the pivoted lever 65. Thus, the locking mechanism of the drum is released and the drum is free to turn. This releasing action of the drum takes place just prior to the engagement of the upper end of the arm 28 with the uppermost stop 50 so that as the upper end of the arm 28 engages said stop, the drum will be rotated through ninety degrees which will be sufficient to discharge the right hand articles 17 carried by the drum into the delivery compartment 22. As the drum is rotated the group of rollers 45 serve to block off the lower ends of the several compartments except the one from which the articles are being discharged into the drum thus maintaining said articles in their compartments for successive discharge therefrom.

It will be understood that the arm 28 travels from its point of rest through an arc of one hundred and eighty degrees, the movement being limited to said one hundred and eighty degrees by the coin controlled mechanism. After the article has been delivered and the handle released, under the influence of a spring 90 the coin controlled mechanism is returned to its normal position carrying the arm 28 in a counter-clockwise direction through one hundred and eighty degrees to its normal position of rest in which it is shown in dotted lines in Figure 6. As it passes to its position of rest its off-set portion 29 cams over the left hand stop in Figure 6 and depresses the same in which position it is retained until a subsequent operation of the machine.

As the drum was rotated in a clockwise direction, the right hand stop 50 in Figure 6 was depressed and passed beneath the tongue 60 until such time as it came into registration with the closed inner end of the arcuate slot 61, whereupon the stop was projected forwardly into the notch 74 of the pivoted lever 65, it being understood that the short end 85 of the arm 28 had, prior to this time passed free of the arm 82 of the lever 80 and permitted both the lever 65 and the lever 80 to return to their normal positions of rest under the influence of their respective springs 71 and 84.

By reference to Figure 3 it will be noted that the machine has been loaded with articles to be dispensed and that the two articles in the drum were taken from the left hand compartment 16. During each operation of the machine, a group of rollers or an article carried by the drum, will prevent articles from the filled compartments entering the drum until the left hand compartment in Figure 3 has been emptied or exhausted whereupon the articles will begin to pass into the drum from the second compartment from the left in Figure 3 until its supply is exhausted

after which the articles pass from the third left hand compartment from the left in Figure 3 and so on until said compartment is exhausted after which the articles will be dispensed into the drum from the extreme right hand compartment in Figure 3.

By the described relation between the drum of the delivery mechanism and the compartments, it is possible to increase the capacity of machines of this type and yet, maintain single delivery of articles from the storage compartments to the delivery mechanism.

From the foregoing it will be apparent that the present invention provides a new and novel vending machine in which the several recited objects of the invention are accomplished and while the invention has been herein described in its preferred form, it is to be understood that it is not to be limited to the specific constructions herein illustrated and that it may be practiced in such other forms as rightfully fall within the scope of the appended claims.

Having thus described the invention, what is claimed is:

1. In a vending machine in combination, a cabinet having a movable front wall for closing the same, a plurality of article containing compartments within the cabinet, a rotary drum mounted beneath the article containing compartments and adapted to receive the articles singly therefrom, a drum supporting shaft rigidly carried by the rear wall of the cabinet and projecting forwardly therefrom, the forward end of said shaft having an axial recess therein, a bracket for supporting the forward end of said drum supporting shaft, operating means carried by said movable front wall, said operating means including a stub shaft adapted for reception in the recess in the forward end of the drum supporting shaft when the movable front wall of the cabinet is in cabinet closing position, a drum operating arm carried by the stub shaft of the actuating means and movable into operative position to rotate the rotary drum when the movable front wall is in position to close the cabinet.

2. In a vending machine in combination, a cabinet having an movable front wall for closing the same, a plurality of article containing compartments within the cabinet, a rotary drum mounted beneath the article containing compartments and adapted to receive the articles singly therefrom, means for revolvably mounting said drum in said cabinet, a plurality of stops carried by one end of said drum, means for successive engagement with said stops to lock the drum against rotary movement, operating means carried by the movable front wall of the cabinet, and means operated by the operating means for operating the drum locking means to effect a release of the drum thereby and for engagement with one of the stops carried by the drum to effect a rotary movement of the drum subsequent to the release of the said locking mechanism.

3. In a vending machine in combination, a cabinet, means within the cabinet for carrying a plurality of articles to be vended, a rotary drum mounted beneath the article carrying means and adapted to receive the articles therefrom and discharge them from the machine, means for revolvably mounting said drum in said cabinet, a plurality of stops carried by one end of said drum, means for successive engagement with said stops to lock the drum against rotary movement, operating means carried by that wall of the cabinet adjacent the end of the drum upon which

the afore-mentioned stops are carried, a stub shaft projecting inwardly of the cabinet from said operating means and adapted to be operated thereby, and an arm carried by said stub shaft and adapted, upon operation of the said operating means, to effect a release of the drum locking mechanism and subsequently to engage one of said stops to effect a rotation of the drum.

4. In a vending machine in combination, a cabinet, means within the cabinet for carrying a plurality of articles to be vended, a rotary drum mounted beneath the article carrying means and adapted to receive the articles therefrom and discharge them from the machine, means for revolutely mounted said drum in said cabinet, a plurality of stops carried by one end of said drum, means for successive engagement with said stops to lock the drum against rotary movement, opening means carried by that wall of the cabinet adjacent the end of the drum upon which the afore-mentioned stops are carried, a stub shaft projecting inwardly of the cabinet from said operating means and adapted to be operated thereby, and an arm carried by said stub shaft and adapted, upon operation of the said operating means, to effect a release of the drum locking mechanism, retain the drum locking mechanism in its inoperative position, effect a rotation of the drum and subsequently release the drum locking mechanism to permit it to return to position to engage one of the stops to again lock the drum

against rotary movement until a subsequent operation of the operating means.

5. In a vending machine in combination, a cabinet, means within the cabinet for carrying a plurality of articles to be vended, a rotary drum mounted beneath the article carrying means and adapted to receive the articles therefrom and discharge them from the machine, means for revolutely mounting said drum in said cabinet, a plurality of stops carried by one end of said drum, means for successive engagement with said stops to lock the drum against rotary movement, operating means carried by that wall of the cabinet adjacent the end of the drum upon which the afore-mentioned stops are carried, a stub shaft projecting inwardly of the cabinet from said operating means and adapted to be operated thereby, and an arm carried by said stub shaft and adapted, upon operation of the said operating means to move through a limited arc, said arm during initial movement through said arc, being adapted to engage the drum locking mechanism to move the latter to drum releasing position, to hold the locking mechanism in drum releasing position during movement of the arm, and upon further movement of the arm to rotate the drum and permit the return of the locking mechanism to its drum locking position.

JACK E. SELLINGER.
HERMAN H. RICHMAN.
